UNITED STATES PATENT OFFICE.

JOHN S. LODER, OF RENO, NEVADA, ASSIGNOR TO LODER SMELTER & REFINER CO., OF RENO, NEVADA, A CORPORATION OF NEVADA.

SMELTING-FURNACE.

948,098.

Specification of Letters Patent.

Patented Feb. 1, 1910.

Application filed April 4, 1908. Serial No. 425,165.

To all whom it may concern:

Be it known that I, JOHN S. LODER, a citizen of the United States, residing at Reno, in the county of Washoe and State of Nevada, have invented certain new and useful Improvements in Smelting-Furnaces, of which the following is a specification.

This invention relates to the smelting of ores and has particular reference to the vertical type of furnace. It embodies a vertical furnace of novel construction which is not heated by solid fuel of any kind, but which has the fuel supplied in fluid form through burners near the bottom of the furnace. The fuel as well as all of the air used to support combustion is supplied under high pressure and results in supporting the ore in the furnace above the combustion space. My invention includes this novel process of operating furnaces of the vertical type.

Some of the broad features of my invention are disclosed in my application 335,094, filed September 18, 1906.

In the accompanying drawings, Figure 1 is an end view partly in section of a furnace embodying my invention; Fig. 2 is a side view of the furnace; and Fig. 3 is a detail of the burner.

My furnace embodies an upper section made up of the vertical refractory walls 1 which are built in the usual way, and which are supported on the angle irons 2 carried by the pillars 3. This upper section has an outlet 5 for products of combustion and an inlet door 4 for the admission of the ore to be treated. Below the lower open end of the upper section there is placed a funnel-shaped lower section 6 made of metal and provided with double walls having a space between them to receive a cooling fluid such as water. The upper end of this funnel-shaped section fits closely against the angle bars 2, and therefore constitutes a continuation of the walls of the upper section. The inner wall of the funnel-shaped section has a shoulder or bulge 7 at the point where the tapered portion joins the straight sided portion. This shoulder 7 projecting into the furnace assists in supporting the ore at that point.

The bottom of the funnel-shaped section is supported on a plate 8, which plate is covered within the furnace by refractory material 9, and this constitutes the floor of the furnace on which the melted material

falls. The plate 8 is supported by jack screws 10 carried by the posts 11, and it will be thus seen that the elevation of the plate may be changed and adjusted at will and that consequently the section 6 may be 60 clamped tightly between that plate and the bottom of the upper section. It will further be noted that this construction produces a furnace which is practically air-tight at its lower part.

Below the shoulder 7 burners 12 enter the furnace, and these burners are supplied with gas for reducing by pipes 13 and with oil for matting through pipes 14. The air necessary to support combustion is supplied 70 through pipes 15, and it is to be understood that means are provided for supplying the fuel and the air to said pipes under high pressure ranging from thirty to sixty pounds to the square inch.

At the bottom of section 6 and on a level with the bottom of the furnace there is a pipe 16 extending through the double walls constituting an outlet for the melted material within the furnace. Constituting a 80 continuation of this pipe there is a water cooled extension 17 U-shaped in vertical transverse section which registers with the inlet opening 18 of the outside car 19. This car 19 is mounted on wheels 20 so that it 85 may be easily removed for purposes of repair, and it is also provided with a spout 21 at the top for the discharge of slag. A water cooled discharge opening 22 for the melted metal is provided in the side of the car. The 90 water for cooling the section 6 and the discharge spouts is supplied through the main pipe 23 and branches 24, 25 and 26, and the water which has been heated is led away by the branches 27, 28 and 29. The pipes 25 95 and 28 may be flexible so as to permit movement of the receptacle 19 or they may be provided with joints which are easily disconnected. It will be understood that the outlets 16 and 22 are to be closed in the usual way such as by the use of clay. It will also be understood that the burners 12 may be made adjustable as in my prior application.

The particular form of furnace shown is long and comparatively thin and is similarly 105 constructed on both sides, having the same inlets and outlets.

In operation the ore charged into the upper part of the furnace strikes the inclined portion of the section 6 and the shoulder 7 110

thereon and is supported in an arch from the shoulder 7 by reason of the high pressure produced below that point by the fuel and air charged into the furnace through the 5 burners 12. It is apparent that by this structure and method of operation there is a free combustion space in the bottom of the furnace immediately beneath the ore, so that the flame plays on the bottom of the ore 10 gradually melting the ore, which at once falls to the floor 9. By this means combustion is localized where the operator may observe its operation through the sight opening, and may control it with great accuracy. 15 This accurate regulation and means for observing the condition of the material at all times is not possible where solid fuel is used in the furnace, since that fuel is distributed over a larger area and the flame extends for 20 some distance up the furnace. The use of gas as fuel furthermore avoids the noxious fumes and gases which result from burning solid fuel in furnaces of this kind.

While the use of gas as the fuel has obvious advantages in the vertical type of smelting furnaces it was not possible to use it practically in the lower part of the furnace until means had been devised for supporting the ore above it, leaving a free combustion space. Furthermore even where the ore was supported above the burner the apparatus was liable to become choked by the melted metal, and it was to avoid these difficulties that the present system and method 35 of operation under high pressure in a closed furnace was devised.

By drawing off the melted ores into the receptacle outside of the furnace and allowing them to settle and separate there I avoid 40 the objectionable agitation which necessarily takes place if it is attempted to perform the separation within the furnace.

Having thus described the invention, what is claimed is:

45 1. The combination in a vertical smelting furnace having a normally closed bottom adapted to receive and maintain gas under pressure, of inwardly inclined sections of the walls of said furnace above the bottom, a 50 shoulder or bulge at the bottom of said inclined sections, burners below said bulge, and means for supplying air and fuel to said burners under pressure.

2. In a smelting furnace the combination with vertical refractory walls having an 55 inlet for material and an outlet for products of combustion near the top, of an inwardly tapering double walled metal continuation of said refractory walls, means for supplying a cooling fluid between said double walls, an 60 inwardly extending bulge on the inner wall at the bottom of said tapering portion, a closed combustion chamber below said bulge, burners discharging into said combustion chamber, and means for supplying air and 65 gas under pressure to said burners.

3. A vertical smelting furnace having a tapering lower portion provided with an inwardly projecting bulge or shoulder at the bottom of said tapering portion, an outlet 70 for the products of combustion at the upper part of said furnace, means for supplying ore thereto, a parallel-sided air tight combustion chamber below said bulge provided with a floor for receiving molten metal, 75 burners extending into said combustion chamber, pipes for supplying air and gas to said burners under pressure in sufficient quantity to support combustion, and means for drawing off the molten material from the 80 bottom of said combustion chamber.

4. A vertical smelting furnace having an inwardly tapering double-walled lower portion, means for supplying a cooling fluid between said double-walls, an inwardly extending bulge on the inner wall at the bottom of said tapering portion, a combustion chamber below said bulge, and means for supplying fuel to said chamber.

5. A vertical smelting furnace having an 90 inwardly tapering double-walled lower portion, means for supplying a cooling fluid between said double walls, an inwardly extending bulge on the inner wall at the bottom of said tapering portion, an air-tight combustion chamber below said bulge, burners discharging into said combustion chamber, and means for supplying air and gas 95 under pressure to said burners.

In testimony whereof I affix my signature 100 in presence of two witnesses.

JOHN S. LODER.
